[57] **ABSTRACT**

An automatic multiple-spindle bar or chucking machine wherein the carrier for work spindles is indexable in an upright support of the machine frame and has a side face beyond which the work supporting ends of the spindles extend. The side face of the support mounts several cross slides movable by cams separably mounted on auxiliary shafts which are journaled in the support and are rotated by an endless chain which is driven by a control shaft mounted in the support at a level above the carrier. The auxiliary shafts transmit motion to rotary, reciprocable and oscillatable additional shafts which extend beyond the side face of the support and can transmit motion to special attachments.

MULTIPLE-SPINDLE MACHINE TOOL

CROSS-REFERENCE TO RELATED APPLICATION

This is a division of my copending application, Ser. No. 671,691 filed Sept. 29, 1967.

BACKGROUND OF THE INVENTION

The present invention relates to machine tools in general, and more particularly to improvements in multiple-spindle machine tools. Still more particularly, the invention relates to horizontal chucking or bar machines with an indexable carrier for a set of work spindles which are suited for treatment of workpieces in rapid sequence with short dwells between successive indexing movements of the spindle carrier.

Presently known multiple-spindle chucking or bar machines normally comprise a frame which defines a completely enclosed work and tool-accommodating space, particularly as seen in the longitudinal direction of the machine. The power train which drives the work spindles is very long and the prime mover for the spindles is remote from the spindles; as a rule, the prime mover is located at that side of the frame which faces away from the aforementioned space. The power train includes a main drive shaft which extends through the spindle carrier and supports the main tool slide. The cross slides receive motion from the prime mover for the spindles through a system of cams, links, levers and rods. The frames of the just described conventional machines are rather sturdy because their parts fully enclose the work and tool-accommodating space; however, such sturdiness is achieved at the expense of accessibility to the working stations and reduces the volume of the aforementioned space. This presents several problems if the machine is to use plural attachments and particularly as regards rapid insertion, interchange or replacement to tools, tool holders, slides, cams and/or workpieces. Furthermore, there is little room for controlled and rapid evacuation of shavings which are removed from workpieces. Moreover, the fact that the power train between the work spindles and the prime mover is very long also creates a number of problems because the parts of the power train are likely to vibrate, to produce excessive noise and to undergo excessive wear if they must be started and arrested at frequent and rapidly following intervals prior and subsequent to rapid acceleration to a high speed which is necessary in rapid treatment of workpieces. The inertia of cross slides, top slides and other relatively heavy parts which receive motion during each stage of a working cycle also contributes to undesirable wear and prevents accurate machining of workpieces at rapidly following intervals. Also, the inertia of heavy parts affects the control shaft which transmits motion to special attachments and other motion receiving devices in a multiple-spindle chucking or bar machine.

SUMMARY OF THE INVENTION

One of the objects of my invention is to provide a multiple-spindle machine tool with a system of drives and motion transmitting units whose inertia is small so that they can transmit motion at frequent intervals and permit rapid acceleration and/or deceleration of driven parts.

Another object of the invention is to provide a novel frame for a multiple-spindle machine and to construct and assemble the essential and optional parts of the machine in such a way that they can be readily reached, inspected, cleaned, interchanged and/or removed with little loss in time.

An additional object of my invention is to provide a multiple-spindle machine tool which is particularly suited for short-lasting treatment of extruded or press-formed workpieces and wherein the removal of shavings does not interfere with accessibility and/or operation of various tools or attachments.

A concomitant object of the invention is to provide simple and lightweight auxiliary drives for attachments which receive rotary, reciprocatory, oscillatory and/or other motion from the main control shaft of a multiple-spindle bar or chucking machine and to assemble such auxiliary drives from a small number of parts.

My invention is embodied in a multiple-spindle machine tool and drive comprises a frame including an upright support or column one side face of which is adjacent to the work and tool-accommodating space, an indexable carrier rotatably mounted in the support, a plurality of work spindles rotatably mounted in the carrier and having work-supporting portions adjacent to the side face of the support, a plurality of cross slides and/or other attachments mounted on the frame adjacent to the side face of the support, a driven control shaft mounted in the frame and preferably located above and parallel to the work spindles, and drive means for operating the attachments including a plurality of auxiliary shafts rotatably mounted in the support in parallelism with the control shaft, means for rotating the auxiliary shafts in synchronism with the control shaft, and cams or analogous motion transmitting means each separately mounted on one of the auxiliary shafts and each arranged to operate one of the attachments in response to rotation of the respective auxiliary shaft.

The novel features which are considered as characteristic of the invention are set forth in particular in the appended claims. The improved machine tool itself, however, both as to its construction and its mode of operation, together with additional features and advantages thereof, will be best understood upon perusal of the following detailed description of certain specific embodiments with reference to the accompanying drawing.

BRIEF DESCRIPTION OF THE DRAWING

FIG. 1 is a perspective view of a multiple-spindle machine tool which embodies one form of my invention, a portion of the frame being broken away directly above the work-accommodating space;

FIG. 2 is an end elevational view of the machine tool as seen from the left-hand side of FIG. 1 and illustrates certain components of the drive for the work spindles;

FIG. 3 is a diagrammatic side elevational view of the drive for the work spindles;

FIG. 4 is an end elevational view of the support with cross and top slides;

FIG. 5 is a horizontal sectional view of the support as seen in the direction of arrows from the line V—V of FIG. 4, showing two types of drives for additional shafts;

FIG. 6 is a fragmentary sectional view of a third drive for an additional shaft;

FIG. 7 is a similar fragmentary sectional view of a fourth drive for an additional shaft which can be used to transmit motion to a heavy top slide;

FIG. 8 is an enlarged horizontal sectional view of a detail of the machine tool shown in FIG. 1;

FIG. 9 is a fragmentary sectional view of the structure shown in FIG. 2;

FIG. 10 is an enlarged end elevational view of an attachment which is connected to an overhanging portion of the frame, the view being taken in the direction of the arrow X shown in FIG. 1; and

FIG. 11 is a section as seen in the direction of arrows from the line XI—XI of FIG. 10.

DESCRIPTION OF THE PREFERRED EMBODIMENTS

Referring first to FIGS. 1 and 2, there is shown an automatic multiple-spindle machine tool which comprises a frame F including a casting 1 forming a base or bed and supporting an upright hollow support or headstock 2 which accommodates a rotary indexable carrier 3 for six equidistant work spindles 5. The mount 4 for the power train of the drive for the spindles 5 in the carrier 3 is bolted to or integral with that side of the headstock 2 which faces away from the working stations. This insures that the carrier 3 and spindles 5 can be indexed and rotated by a very short power train. The prime mover 6 of the drive is preferably an electric motor which is mounted on the bed 1 and transmits motion through a belt drive 7, a transmission including a gear train having gears 8 to 15 in the mount 4 (see particularly FIG. 3) and a planetary including a sun wheel 16 and planet pinions 17. The pairs of meshing gears 10, 11 and 12, 13 are readily accessible and replaceable to change the transmission ratio.

The machine tool further comprises one or more cross slides, for example two cross slides 18, 18a, which receive motion in a manner as illustrated in FIGS. 4 and 5. A driven horizontal main camshaft or control shaft 19 which receives motion from the motor 6 and is mounted in the frame F at a level above the carrier 3 is provided with a driver gear 20 which drives a torque transmitting element here shown as an endless chain 22. This chain can be replaced by a ring gear (not shown) surrounding the spindle carrier 3 and in mesh with the driver gear 20. The chain 22 can be tensioned by means of two tensioning rolls 20a mounted on the headstock 2 and movable radially with reference to the axis of the carrier 3. The chain 22 is trained around driven gears 23 which are affixed to secondary camshafts or auxiliary shafts 24 for the cross slides and each of which preferably comprises the same number of teeth as the driver gear 20. Each auxiliary shaft 24 carries a separable and exchangeable motion transmitting cam 25 serving to transmit motion to a cross slide. The cross slides 18, 18a are of different design (see FIG. 1) so that each thereof can carry one or more different tool holders for material removing tools. These cross slides are exchangeable and can be mounted at different locations, i.e., adjacent to the work-supporting ends of selected spindles 5. FIG. 4 shows a total of six cross and top slides, including the cross slides 18, 18a and four additional cross slides 18d,

but the number of these cross slides can be less, depending on the desired number of operations to which the workpieces are to be subjected during a complete cycle. The cross slide 18a is flat and is designed to receive and to retain a tool holder at one of its ends, i.e., adjacent to the work-supporting end of the respective spindle 5. The cross slide 18 is L-shaped and is designed to carry tool holders at several distances from the work-supporting end of the adjoining spindle 5.

Other types of cross slides can be employed with equal advantage and each of the illustrated cross slides can switch positions with any one of the other five cross and top slides.

As shown in FIG. 5, the control shaft 19 can further transmit motion to one or more attachments. One of the auxiliary shafts 24 carries a cylindrical cam 29 provided with an endless peripheral cam groove 30 which receives a roller follower 31 installed in a bearing member 31a which is affixed to a reciprocable additional shaft 32 mounted in the headstock 2. When the control shaft 19 drives the gear 20, it also drives the cam 29 whereby the follower 31 causes the additional shaft 32 to move back and forth and to operate an attachment 132 whose operation necessitates a reciprocatory movement. An arm 33 holds the shaft 32 against rotational movement. The right-hand end portion of the shaft 32 extends beyond the right-hand side face of the headstock 2.

The auxiliary shaft 24 shown in the lower part of FIG. 5 carries a driver gear 26 meshing with a driven gear 27 on a further additional shaft 28 which transmits rotary motion to another attachment 232. Since the gear 23 on the shaft 24 has the same number of teeth as the driver gear 20 on the control shaft 19, the additional shaft 28 can be rotated at the same speed as the control shaft, at a higher speed or at a lower speed but always proportionally to the speed of the control shaft. It is clear that the gear 26 can be mounted directly on the control shaft 19, that the cam 29 can be mounted on the control shaft, or that each of the shafts 19, 24 can carry a cam or gear to transmit motion to a suitable attachment. The right-hand end portion of the additional shaft 28 extends beyond the right-hand side face of the headstock 2.

FIG. 6 shows that an auxiliary shaft 24 can also support a face cam 34 having an endless cam groove 35 machined into one of its end faces and accommodating a roller follower 36 mounted on an arm 37 which is affixed to an additional shaft 38 serving to rock or oscillate a further attachment 332 (indicated by phantom lines). Thus, the control shaft 19 and/or one or more shafts 24 can operate attachments (132, 232, 332) which require rotary, reciprocatory and/or pivotal movement for their operation. The three motion transmitting structures of FIGS. 5 and 6 can be installed in a fully assembled machine tool having the basic design of FIG. 1 or they may be permanently or removably or exchangeably installed during initial assembly of the machine tool. Thus, the cams 29, 34 and the gear 26 can be removed or interchanged so that each attachment can be installed in any one of several possible positions to remove material from successive workpieces at one of the six working stations adjacent to the illustrated end of the carrier 3 shown in FIG. 1. The dimensions (or at least the diameters) of the additional

shafts 32, 28, 38 are preferably identical so that each thereof can be installed in either one of several sets of bearings or journals provided therefor in or on the headstock 2. One end portion of the additional shaft 38 extends from the headstock and can be separably coupled to the attachment 332.

A relatively heavy top slide or cross slide 45 (see FIG. 7) which can be used to carry a tool holder for tools which remove material from workpieces held in one of the two uppermost spindles 5 shown in FIG. 1 can receive motion from an auxiliary drive which includes a rotary face cam 39 having an endless cam groove 40 for a roller follower 41 mounted on a two-armed lever 42 having a toothed segment 43. The top slide 45 is mounted on an elongated overhanging extension or arm 21 which is bolted to or is integral with the headstock 2 and extends above the space S for the workpieces and tools. The segment 43 meshes with a rack 44 on the top slide 45 and transmits to the latter a reciprocatory movement in response to oscillatory movement of the lever 42. The arm 21 can support two top slides 45. The cam 39 is mounted directly on the control shaft 19 which extends through the arm 21. FIG. 8 shows that the control shaft 19 can carry two cams 39, one for each of the two top slides mounted on the arm 21. However, it is clear that all of the six cross and top slides shown in FIG. 1 can be mounted on the headstock 2 and that the cams 39 can be dispensed with.

The main or longitudinal tool slide 47 of the machine tool is movable by a carriage 48 (FIG. 1) which receives motion from a cylindrical cam 49 mounted on the control shaft 19 (see FIG. 8). The roller follower which extends into the endless circumferential groove of the cam 49 and is affixed to the carriage 48 for the main slide 47 is not shown in the drawing. The just mentioned follower can also be affixed to a spindle (not shown) which is connected to the carriage 49 and is reciprocable in the arm 21. Such spindle can be mounted in the arm 21 at a level above the slide 47 and below the cam 49. The arm 21 carries bearings 50 for the control shaft 19 and the latter's right-hand end portion extends into a hollow bearing block 51 and carries a bevel gear 52 meshing with a bevel gear 53 on a transverse horizontal second control shaft 54. The bearing block 51 is mounted on or is integral with the free end of the arm 21. The end portions of the second control shaft 54 extend into a pair of housings 56 provided on the block 51 and carry pairs of cams 55 each of which can transmit motion to a further attachment (not shown). The bevel gear 52 and the parts receiving motion therefrom are preferably removable, i.e., the entire structure shown at the left-hand end of the arm 21 in FIG. 8 can be installed on an operative machine. As a rule, the second control shaft 54 will be fully assembled with and in the parts 51, 53, 55, 56 and such attachment can be bolted to or detached from the arm 21.

The main slide 47 can support one or more additional attachments which can be operated in synchronism with the work spindles 5 or at a predetermined ratio to the speed of these spindles. FIGS. 9 to 11 illustrate one of the attachments which can be mounted on the main slide 47. The gear 15 and sun wheel 16 of FIG. 3 are mounted on a hollow main drive

shaft 58 (FIG. 9) having an internally splined end portion 60 adjacent to the corresponding end of the carrier 3. This splined end portion 60 can receive the externally splined end of an auxiliary shaft 59 which can be inserted into a hollow cylindrical guide or sleeve 57. The latter extends axially through the carrier 3 and its other end is installed in the bearing block 51 (see FIG. 11). The right hand end of the auxiliary shaft 59 carries a gear 61 meshing with a gear 62 on the input shaft 63a of an attachment 63. The casing of the attachment 63 can be bolted to one of several facets 64 at the lower end of the bearing block 51 (see FIG. 10). The attachment 63 may constitute a high speed drilling or boring machine and its input member 63a may but need not rotate at the exact speed of the main drive shaft 58. The gears 61, 62 are accessible to change the ratio between the shaft 59 and input member 63a. It is further clear that the gears 61, 62 can be replaced by a variable-speed transmission and that the motion transmitting connection between the attachment 63 and main drive shaft 58 may include one or more clutches so that the attachment 63 can remain mounted on the frame F but is disconnected during certain types of operations. The same applies for the previously described attachments each of which can be provided with a clutch and/or with a variable speed transmission.

FIG. 1 further shows a large shavings-collecting chamber 65 which is provided in the bed 1 in the region below the work-supporting ends of the spindles 5 and the slides. Rapid evacuation of shavings from the chamber 65 can be effected by a suitable conveyor 66. Since the work and tool-accommodating space S (to the right of the headstock 2 as viewed in FIG. 1) is rather large and is fully open from the front side of the frame F (facing the viewer of FIG. 1) as well as from below (toward the chamber 65), the mounting or removal of special attachments, insertion or removal of tools or their holders, as well as interchange, mounting or removal of slides and the feed and evacuation of workpieces present no problems. Moreover, the machine tool may carry an exceptionally large number of special attachments and/or slides without the danger of interference. Each attachment can receive motion through the intermediary of a relatively short and hence light power train so that the inertia of moving parts is relatively small.

In heretofore known multiple-spindle machine tools, the cross slides and top slides normally receive motion through several levers, bars, push rods, links and like devices. In my improved machine, the control shaft 19 can transmit torque to the shafts 24 which move the cross slides back and forth by means of simple, lightweight and exchangeable motion transmitting cams 25 so that the means which drive the cross slides can change direction very rapidly and can be quickly decelerated to zero speed or accelerated to a high speed without excessive wear, noise and/or vibration. Since a large part of the drive for the work spindles 5 is accommodated directly in the portion 4 of the headstock 2, the power train between the prime mover 6 and the work spindles 5 is very short. This power train also drives the control shaft 19 and can be utilized to operate the indexing mechanism for the spindle carrier 3. The end portions of additional shafts 28, 32, 38 extend into the tool and work-accommodating space S so

that they can be rapidly coupled to or uncoupled from special attachments which might be needed in connection with certain types of treatment. Such attachments may include end-working attachments, threading attachments, high-speed drilling attachments, cross-milling or cross-drilling attachments, reaming attachments, and/or others.

In the appended claims, the term "attachment" is intended to embrace the attachments 132, 232, 332, 63, other attachments which can receive motion from the auxiliary shafts 24, the slides 18, 18a, 18d and/or other types of slides adapted to receive motion from the shafts 19 and 24.

Without further analysis, the foregoing will so fully reveal the gist of the present invention that others can, by applying current knowledge, readily adapt it for various applications without omitting features which fairly constitute essential characteristics of the generic and specific aspects of my contribution to the art and, therefore such adaptations should and are intended to be comprehended within the meaning and range of equivalence of the claims.

What is claimed as new and desired to be protected by Letters Patent is set forth in the appended claims:

1. In a multi-spindle machine tool, a combination comprising a frame including an upright support having a side face; an indexable carrier rotatably mounted in said support; a plurality of workspindles rotatably mounted in said carrier and having supporting portions adjacent to said side face; a plurality of attachments supported by said frame and adjacent to said side face; a driven control shaft mounted in said frame; drive means for operating said attachments in response to rotation of said control shaft, including a plurality of auxiliary shafts rotatably mounted in said support in parallelism with said control shaft, means for rotating said auxiliary shafts in synchronism with said control shaft, and a plurality of motion transmitting means each separably connected with one of said auxiliary shafts and each arranged to operate one of said attachments in response to rotation of the respective auxiliary shaft; an additional shaft reciprocably mounted in said support and having a portion extending beyond said side face; and additional drive means comprising cam and follower means arranged to reciprocate said additional shaft in response to rotation of one of said auxiliary shafts.

2. A combination as defined in claim 1, further comprising means for holding said additional shaft against rotation with reference to said support.

3. A combination as defined in claim 1, wherein said cam and follower means comprises a cylinder cam fixed to said one shaft and having an endless peripheral cam groove and a follower fixed to said additional shaft and extending into said groove.

4. In a multi-spindle machine tool, a combination, comprising a frame including an upright support having a side face; an indexable carrier rotatably mounted in

said support; a plurality of workspindles rotatably mounted in said carrier and having work-supporting portions adjacent to said side face; a plurality of attachments supported by said frame and adjacent to said side face; a driven control shaft mounted in said frame; drive means for operating said attachments in response to rotation of said control shaft, including a plurality of auxiliary shafts rotatably mounted in said support in parallelism with said control shaft, means for rotating said auxiliary shafts in synchronism with said control shaft, and a plurality of motion-transmitting means each separably connected with one of said auxiliary shafts and each arranged to operate one of said attachments in response to rotation of the respective auxiliary shafts; an additional shaft oscillatably mounted in said support means and having one portion extending beyond said side face; and additional drive means comprising means for oscillating said additional shaft in response to rotation of one of said auxiliary shafts.

5. A combination as defined in claim 4, wherein said means for oscillating comprises a face cam fixed to said one shaft and having an endless cam groove, and a pivotable arm secured to said additional shaft and having a follower extending into said groove.

6. In a multi-spindle machine tool, a combination comprising a frame including a single upright support having a side face; an indexable carrier mounted in said support; a plurality of workspindles rotatably mounted in said carrier and having work-supporting portions adjacent to said side face; a plurality of attachments supported by said frame and adjacent to said side face; a driven control shaft mounted in said frame; drive means for operating said attachments in response to rotation of said control shaft, and including a plurality of auxiliary shafts rotatably mounted in said support in parallelism with said control shaft, means for rotating said auxiliary shafts in synchronism with said control shaft and comprising a plurality of gears respectively fixedly mounted on said control shaft and said auxiliary shafts and an endless chain wound about said gears, and a plurality of motion transmitting means each separably connected with one of said auxiliary shafts and each arranged to operate one of said attachments in response to rotation of the respective auxiliary shaft; an additional shaft movably mounted in said support and having a portion extending beyond said side face; and additional drive means for moving said additional shaft in response to rotation of one of said auxiliary shafts.

7. A combination as defined in claim 17, wherein said additional drive means includes a gear train and wherein said additional shaft is rotatable by said gear train with reference to said support in response to rotation of said one auxiliary shaft.

8. A combination as defined in claim 7, wherein said support is hollow and said gear train is mounted in the interior of said support.
